UNITED STATES PATENT OFFICE

JOSEPH C. McCUNE, OF EDGEWOOD, PENNSYLVANIA, ASSIGNOR TO THE WESTINGHOUSE AIR BRAKE COMPANY, OF WILMERDING, PENNSYLVANIA, A CORPORATION OF PENNSYLVANIA

AUXILIARY-RESERVOIR RELEASE VALVE

Application filed January 10, 1929. Serial No. 331,477.

This invention relates to release valves and more particularly to a valve device for effecting the release of fluid under pressure from the auxiliary reservoir of a fluid pressure brake system.

An object of the invention is to provide an improved release valve device having an unrestricted atmospheric vent that is not apt to clog with dirt or other foreign matter.

Another object of the invention is to provide a valve device of the character specified with improved actuating mechanism.

Another object of the invention is to provide a release valve device of the character mentioned which is simple in construction, and reliable and exact in function under all conditions of service.

The invention also comprises certain new and useful improvements in the construction, arrangement and combination of the several parts of which it is composed, as will be hereinafter more fully described and claimed.

In the accompanying drawings; Figure 1 is a plan of a release valve device constructed according to the invention; and Fig. 2 is a vertical longitudinal section thereof.

Referring to the drawings, the release valve device may comprise a casing 11 having a chamber 12, containing a release valve 13 adapted in its seated position to engage a seat ring 14 and cut off communication between chamber 12 and a chamber 22 open to the atmosphere through an opening 23.

The casing 11 is secured by screw-threads to a plug 15 which is screwed into a threaded opening 16 of the auxiliary reservoir 17 and which is provided with a passage 18 connecting the auxiliary reservoir with the chamber 12.

The valve 13 has a stem 19 which projects through an opening in the end wall of the casing 11, and has a cap 20 screw-threaded to the end thereof.

As shown in Fig. 2, the skirt of the cap 20 encloses the portion of the stem 19 projecting beyond the casing 11 and a coil spring 21 which encircles the stem 19 and urges the valve 13 toward the seat ring 14.

The rim of the skirt of the cap is spaced a suitable distance from the end wall of the

casing when the valve 13 is seated, and when the valve is moved away from the seat ring 14, the rim of the skirt of the cap engages the end wall of the casing 11 to limit the inward movement of the valve 13, as will be readily understood.

The casing 11 is provided with a pair of spaced bracket plates 24 carrying pins 25 and 26 on which levers 27 and 28 are pivotally mounted.

The levers 27 and 28 may be in the form of bell cranks. One arm 29 of the lever 27 may be connected to an operating rod 30, while the other arm 31 of said lever may extend over the end wall of the cap 20, and be forked, as shown best in Fig. 1.

The lever 28 has one arm 32 connected to an operating rod 33, and another arm 34 which extends over the end wall of the cap 20 and is disposed between the forks of the arm 31 of the lever 27.

The rods 30, 33 extend to the opposite sides of the vehicle and the construction and arrangement of the parts is such that when either of these rods is operated in the usual well known manner, either of the levers 27, 28 will be actuated to depress the cap 20, thereby unseating the valve 13 and releasing the fluid in chamber 12.

While one illustrative embodiment of the invention has been described in detail, it is not my intention to limit its scope to that embodiment or otherwise than by the terms of the appended claims.

Having now described my invention, what I claim as new and desire to secure by Letters Patent, is:—

1. In a fluid pressure release valve device, the combination with a casing and a valve mounted in said casing and having a stem projecting therethrough, of means disposed exteriorly of the casing for urging said valve toward its seat, means for operating the valve, and means carried by the projecting portion of the valve stem for limiting the movement of the valve away from its seat.

2. In a fluid pressure release valve device, the combination with a casing and a valve mounted in said casing, of a stem carried by said valve and projecting through the casing,

a cap fixed to the extremity of the stem and being spaced from the casing when the valve is seated, means disposed exteriorly of the casing for urging said valve toward its seat, and means engaging the exterior of said cap for operating said valve, the movement of the valve away from its seat being arrested when the cap engages the casing.

3. In a fluid pressure release valve device, the combination with a casing and a release valve mounted in said casing, of a stem carried by said valve and projecting through the casing, a cap mounted on the extremity of the valve stem and having a skirt surrounding the major portion of the valve stem projecting from the casing, the rim of the skirt being spaced from the casing when the valve is seated, a spring encircling the valve stem and disposed within the cap, and means engaging said cap for operating the valve, the movement of the valve operating means being limited when the rim of the cap skirt engages the casing.

In testimony whereof I have hereunto set my hand this 7th day of January, 1929.

JOSEPH C. McCUNE.
